UNITED STATES PATENT OFFICE.

CHARLES WARNER, OF PHILADELPHIA, PENNSYLVANIA.

DESIGN FOR A COMB.

54,151.

Specification for Design.

Patented Nov. 4, 1919.

Application filed March 14, 1919. Serial No. 282,750. Term of patent 14 years.

To all whom it may concern:

Be it known that I, CHARLES WARNER, a citizen of the United States, residing at Philadelphia, in the county of Philadelphia and State of Pennsylvania, have invented a new and original and ornamental Design for a Comb, of which the following is a specification, reference being had to the accompanying drawing, forming a part thereof.

I claim:

The ornamental design for a comb, as shown.

CHARLES WARNER.

Witnesses:

Mrs. G. F. TORCHIO,
Mrs. CHAS. WARNER.
